UNITED STATES PATENT OFFICE.

GUY S. CLARKSON, OF WINNIPEG, MANITOBA, CANADA, ASSIGNOR TO DAVID R. FINKELSTEIN, OF WINNIPEG, MANITOBA, CANADA.

PROPELLER FOR DISHWASHING MACHINES.

Application filed September 25, 1923. Serial No. 664,761.

To all whom it may concern:

Be it known that I, GUY S. CLARKSON, of the city of Winnipeg, in the Province of Manitoba, Canada, have invented certain new and useful Improvements in Propellers for Dishwashing Machines, of which the following is the specification.

- The invention relates to improvements in dish washing machines and particularly to 10 the propeller or dasher and the tank bottom in which the propeller operates, and an object of the invention is to provide a double bladed propeller which will throw the water forcibly upwardly at a high velocity 15 and will distribute the same throughout the area of the tank so that all the dishes within the tank are subjected, on the both faces thereof, to a passing cleansing stream of water.
- 20 A further object is to construct a propeller which will throw the water in a spiraling stream between the dishes, the water striking the top of the tank and being deflected outwardly and subsequently returning 25 to the bottom of the tank down the side walls thereof.

With the above more important objects in view the invention consists essentially in the arrangement and construction of parts hereinafter more particularly described, reference being had to the accompanying drawings in which:

Fig. 1 is an interior view of the upper part of the casing, part of the front thereof having been torn away.

Fig. 2 is a plan view of the casing with the cover removed and showing the position of the dishes in the rack.

Fig. 3 is a perspective view of the propeller.

Fig. 4 is an enlarged detailed vertical sectional view through the propeller, the section being taken at 4-4' Figure 1.

Fig. 5 is an enlarged detailed vertical sectional view through the propeller, the section being taken at 5-5' Figure 1.

In the drawing like characters of reference indicate corresponding parts in the several figures.

50 The dish washing machine presents a cylindrical sheet metal body 1 which is provided at the top with an internal ledge 2 receiving a removable cover 3. The body is mounted on suitable casters 4 and internal-

ly is provided with an elevated bottom 5 which provides a washing tank 6. The bottom of the tank is shallow saucer shaped and presents an outer gradually inclining rim 7 and a central well 8. Within the tank the dish washing rack 9 is mounted, such 55 rack supporting the plates 10, in inner, outer and intermediate rows. Here it will be observed that the plates are in an inclined position with their upper edges tilted outwardly and that the plates of the various 60 rows are approximately parallel, a comparatively wide space being reserved between the rows of the plates to permit of the free flow of water. A two bladed propeller 11 is 65 located centrally within the bottom of the tank and operates within the well and is carried by a driving shaft 12 extending through the bottom of the tank and driven in any suitable manner. In this connection 70 I might remark that the shaft 12 is usually driven by an electric motor housed within the bottom of the outer casing. The propeller is preferably a cast one and it is provided centrally with a sleeve or socket 13 75 which receives the upper end of the shaft 12, the propeller being fastened to the shaft by a pin 14. The blades of the propeller, two in number, are identically constructed and integrally cast with the sleeve, it being here observed that the lower edge 15 of each blade is more or less horizontal and that the upper edge 16 is inclined, with the result that the blades are much wider at the centre than at the outer ends. In vertical 80 section each blade is for the greater part of an ogee shape, the curve 17 at the upper edge being long at the centre and gradually shortening at the outer end of the blade 85 where it merges into the vertical part of the body. The curve 18 at the lower edge of each blade is more abrupt than that of the upper edge, but it remains more or less constant throughout the length of the blade. The outer end or tips 19 of the blades are curved gradually forwardly in respect to the direction of rotation of the blades and it will be also observed that the upper inner 90 part of each blade is provided with a more or less V-shaped wing 20 which is slightly inclined to the vertical and is positioned at right angles to the top of the blade. The inner ends of the wings are connected by 95 a centrally positioned web 21. Both the 100

105

top and bottom edges of the blades are sharpened as indicated at 22 and 23.

The propeller is rotated at a comparatively high speed in a clock-wise direction 5 and the water, which is picked out of the well by the lower edges of the blade wings, is thrown upwardly and passes in parallel streams in the form of spray between the plates. In this connection I might point 10 out that the upper edges of the blades are positioned practically at right angles to the lower edges of the plates in the rack and on this account the dishes do not materially stop the flow of water. The up-going water, 15 after having passed between the sets of plates, is deflected outwardly by the cover and returns to the bottom of the tank down the outside wall thereof. This down-going stream of water washes the rear sides of the 20 outer row of plates. I might say that in actual demonstration the up-going water has a spiralling course of travel between the plates and that the down-going water has a slightly spiralling direction of travel.

25 With this particular type of propeller the water is evenly distributed throughout the plate containing area of the tank and it throws the water at a high velocity and is accordingly particularly effective in washing the plates.

The well maintains the greatest volume of water at the point where the blade is operating and the shallow rim 7 feeds the down-coming water to the well.

35 A drain off pipe 24 leads from the well to the exterior of the tank and is provided at its outer end with a tap or drain cock 25.

What I claim as my invention is:

40 1. A propeller for dish washing machines comprising a vertically disposed blade presenting a substantially horizontal and forwardly curved lower edge and a rearwardly

curved inwardly and upwardly inclined upper edge.

2. A propeller for dish washing machines 45 comprising a vertically disposed blade of a varying ogee shape in vertical section, the outer tip of the blade being narrow and the inner parts being relatively wide.

3. In a dish washing machine, a propeller 50 comprising a pair of vertically disposed oppositely extending blades connected at their inner ends, said blades having their lower edges substantially horizontal and their upper edges inclined upwardly and converging towards the center of the machine, the said lower edges of the blades being curved forwardly and the said upper edges thereof curved rearwardly and the outer tips of said blades being curved forwardly. 55

4. In a dish washing machine, a two bladed propeller having the blades of an ogee shape in vertical cross-section and both with their lower edges horizontal and their upper edges inclining upwardly and inwardly, the tips of the blades being forwardly hooked and the upper central portions of the blades being connected by a cross web. 60

5. In a dish washing machine, a two 70 bladed propeller provided centrally with a vertical socket and having the lower edges of the blades contained in the same horizontal plane and the upper edges of the blades inclining inwardly and upwardly, 75 and said blades being of an ogee shape in vertical cross-section and having their outer tips forwardly curved and their upper inner portions connected above the socket by a cross web. 80

Signed at Winnipeg, this 10th day of July, 1923.

GUY S. CLARKSON.
